UNITED STATES PATENT OFFICE.

RUDOLPH J. MITCHELL, OF JENKINTOWN, PENNSYLVANIA.

WINDOW.

SPECIFICATION forming part of Letters Patent No. 565,118, dated August 4, 1896.

Application filed April 13, 1896. Serial No. 587,335. (No model.)

To all whom it may concern:

Be it known that I, RUDOLPH J. MITCHELL, a resident of Jenkintown, in the county of Montgomery and State of Pennsylvania, have 5 invented certain new and useful Improvements in Windows; and I do hereby declare the following to be a full, clear, and exact description of the invention, such as will enable others skilled in the art to which it appertains

10 to make and use the same.

My invention relates to an improvement in windows and more particularly to such in which the sashes are adapted to move vertically and also swing on hinges, the object of 15 the invention being to provide simple and efficient means whereby one edge of the sash can be automatically released from the sash-cord when said sash is swung, open said devices also acting automatically to attach the 20 free edge of the sash to the cord when the sash is closed.

A further object is to so construct and mount a sliding and swinging sash that the 25 hinges will be concealed from view.

25 A further object is to provide a simple, cheap, and efficient stop and bottom support for the sash or sashes.

30 A further object is to provide sliding and swinging sashes with improvements which shall be simple in construction, easy to operate, and which shall be effectual in all respects in the performance of their functions.

With these objects in view the invention 35 consists in certain novel features of construction and combinations and arrangements of parts, as hereinafter set forth, and pointed out in the claims.

In the accompanying drawings, Figure 1 is 40 a view of a window frame and sashes, showing the application of my improvements thereto. Fig. 2 is a vertical sectional view. Figs. 3 and 4 are horizontal cross-sections, and Figs. 5 and 6 are detail views.

45 A represents a window-frame having the usual weight-boxes and pulleys for the accommodation of the weighted cords 1 which counterbalance the sashes B C, each sash being adapted to be hinged at one edge and having a sash-cord detachably connected with its 50 other edge.

The inner sash B is preferably attached to the window-frame when in its normal position

by means of hinges B'. Each hinge B' comprises an open eye or hook 2, attached to the window-frame, and a curved plate 3, attached 55 to the sash, said curved plate having an enlarged portion 4 at its free edge to be engaged by the eye or hook 2 and a slot or opening 5 in rear of said enlarged portion for the reception of said eye or hook when the sash is swung 60 open. By thus constructing the hinges B' and attaching them to the window-frame and sash they will be concealed from view by the bead 6 and the sash can be swung open around the bead. 65

To permit the sash B to be raised and lowered, the inner face of the bead 6 is made with a groove 7 for the accommodation of the hinge, and when the sash is raised or lowered the part of the hinge attached to the sash will 70 move freely in said groove 7.

The hinge B' may be made of cast metal or of sheet metal, as desired. The hinges C', by which the sash C is adapted to be hinged to the parting-rail 8, may be constructed in the 75 same manner as above described, but in the drawings I have shown said hinges C' constructed of sheet metal. The parting-rail 8 is made with an outer beveled face 9, to which the eyes or hooks of the hinges are 80 attached, so that said sash C can be swung open without engaging or binding against said bead.

It will be seen that when the sashes are 85 moved up and down the portions of the hinges attached thereto will ride freely into or out of engagement with the parts of said hinges which are attached to the window-frame. In order to permit the sash B to be swung on its hinges, the lower portion 10 of the bead 11 is 90 hinged to the window-frame, so that it can be turned back out of the way of the free edge of said sash.

Any suitable form of hinges may be employed for connecting the portion 10 of the 95 bead to the frame A.

For the purpose of permitting the outer sash C to be swung on its hinges, the lower portion 12 of the parting-bead 13 is hinged so that it can be turned back out of the way 100 of the free edge of the sash C when the latter is lowered.

Sash-cords 14 are permanently attached to the hinged edge of the sashes, but the cords

1 are adapted to be removably attached to the free edges of the sashes, as above intimated. Each sash-cord 1 is adapted to move in grooves 15 in the frame and are provided at their lower ends with sleeves 16, preferably of metal. From each sleeve, either at a point between its ends or at its lower end, an arm or pin 17 projects laterally, and when the sashes are lowered and swung open on their hinges said pins or arms 17 are adapted to engage the lower ends of the plates 18, the latter being secured to the window-frame and made to project over the grooves 15. The free edge of each sash is recessed for the reception of a slotted plate 19, having a beveled lip 20, the upper and lower beveled faces 21 22 of which serve as guides for conducting the pin or arm 17 properly to the slot or socket 23 in said plate 19.

20 When the sash is lowered and the hinged bead turned back from the free edge thereof, the sash can be swung open on its hinged edge, as above explained, and when it is being thus swung on its hinges the lip 20 of the plate 19 will engage the pin or arm 17 and cause it to project under the lower end of the plate 18, and thus the weighted sash-cord 1 is automatically detached from the free edge of the sash and connected with the window-frame in position to again receive the sash when the latter is closed.

When the sash is swung back to its normal position, the free end of the pin or arm 17 will enter the slot or socket in the plate 19 and be pushed by the wall 24 of said slot or socket out of engagement with the plate 18, thus automatically attaching the sash-cord 1 to the sash.

In order to insure the proper alinement of the arm or pin 17 with the slotted or socketed plate 19, a hinged stop 25 is attached to the sill of the window-frame and adapted to be moved longitudinally, so as to enter a recess 26 in the bottom rail or bead 27, whereby to retain said stop in proper position. The stop 25 may be conveniently made of an ordinary butt-hinge and serves not only as a stop but also to sustain the weight of the sashes when the latter are lowered, and thus takes all weight of the sashes off of the hinges when the sashes are swung open.

My improvements are very simple in construction, comprise few parts, are cheap to manufacture, not liable to get out of order, are neat in appearance, and are effectual in all respects in the performance of their functions.

Various slight changes might be made in the details of construction without departing from the spirit of my invention or limiting its scope, and hence I do not wish to limit myself to the precise details herein set forth; but,

Having fully described my invention, what I claim as new, and desire to secure by Letters Patent, is—

1. The combination with a window-sash hinged at one edge and a sash-cord, of devices

constructed and adapted to automatically detach said sash-cord from and attach it to the sash and operated by turning the latter on its hinges, substantially as set forth.

2. The combination with a vertically-sliding sash and a sash-cord, of means for hinging said sash when the latter is lowered and means constructed and adapted to automatically detach said sash-cord from or attach it to the sash and operated by turning the latter, substantially as set forth.

3. The combination with a sash hinged at one edge, and a sash-cord, of an arm or pin projecting from the free end of said cord, a device on the sash to receive said arm or pin and a plate or catch on the window-frame, said device on the sash being so constructed and arranged that when said sash is swung open, it will move the arm or pin in engagement with the plate or catch on the window-frame and when the sash is closed said device thereon will move the arm or pin on the sash-cord out of contact with said plate and attach it to the sash, substantially as set forth.

4. The combination with a vertically-movable sash hinged at one edge, and a sash-cord, of means for automatically detaching said sash-cord from and attaching it to the sash when the sash is turned on the hinge, and a stop to limit the downward movement of the sash, substantially as set forth.

5. The combination with a window-frame, a vertically-movable sash hinged thereto and a sash-cord, of a lateral arm or pin at the free end of said cord, a plate secured to the frame and adapted to be engaged by said arm or pin, and a socketed plate secured to the free edge of the sash and adapted, when the sash is swung on its hinges, to move said arm or pin out of engagement with the sash and into engagement with the plate on the window-frame, or vice versa, accordingly as the sash is swung open or closed, substantially as set forth.

6. The combination with a sash hinged at one edge and a sash-cord, of an arm or pin projecting laterally from the free end of said cord, a plate secured to the window-frame, to be engaged by said arm or pin, and a socketed plate secured to the free edge of the sash, said plate having a beveled lip and beveled faces above and below said lip, substantially as set forth.

7. The combination with a sash hinged at one edge to a window-frame, and a sash-cord, of a sleeve at the free end of said cord, an arm or pin projecting laterally from said sleeve, a socketed plate on the free edge of the sash adapted to receive said arm or pin, said plate having a lip, and a catch on the window-frame to receive said arm or pin when the sash is swung open, substantially as set forth.

8. The combination with a window-frame, and a sash hinged at one edge to the frame, of a hinged device attached to the frame at the bottom of the horizontal groove in the lat-

ter, and adapted to be swung upward to a vertical position to form a stop for the sash and sustain its weight when the latter is swung open, whereby to take the weight of the sash off of its hinges, substantially as set forth.

5 9. The combination with a window-frame and a vertically-movable sash hinged at one edge to the window-frame, of a sash-cord, an arm or pin at the free end of said cord, a plate secured to the frame and acting as a catch for said arm or pin, a socketed plate secured to the sash and adapted to receive said arm or pin, and a hinged stop to limit the downward movement of the sash whereby to insure the 15 alignment of the socketed plate on the sash with the arm or pin on the cord, substantially as set forth.

10 10. The combination with a window-frame and a vertically-movable sash hinged at one edge to the frame, of a hinged device attached to the sill of the frame and serving as a stop for the sash and also to sustain the weight thereof when lowered, one member of said hinged device having a longitudinal movement and adapted to enter a notch or recess in the bottom bead of the frame, substantially 25 as set forth.

11 11. The combination with a window-frame, a parting-bead having a beveled face and a vertically-movable sash, of hinges for con-

necting said sash with said bead when the sash is lowered, each hinge comprising an open eye or hook secured to the beveled face of the bead and a curved plate having a slot and an enlarged edge, secured to the sash, 35 substantially as set forth.

12 12. The combination with a window-frame having grooves in one edge thereof, a vertically-movable sash hinged at one edge to the window-frame and a sash-cord, of a sleeve 40 secured to the free end of said cord and adapted to move in said groove in the frame, an arm or pin projecting laterally from said sleeve, a plate secured to the frame and adapted to project over said groove, and a device 45 on the sash adapted to engage said arm or pin, whereby when the sash is swung in one direction the arm or pin will be moved in contact with said plate and when the sash is swung in the other direction said arm or pin 50 will be moved out of engagement with said plate and be attached to the sash, substantially as set forth.

In testimony whereof I have signed this specification in the presence of two subscribers.
